Inventor:

Herman A. Brassert,

By *Herman A. Brassert*

UNITED STATES PATENT OFFICE

HERMAN A. BRASSERT, OF KENILWORTH, ILLINOIS, ASSIGNOR TO H. A. BRASSERT & COMPANY, OF CHICAGO, ILLINOIS, A CORPORATION OF ILLINOIS

CHECKER CONSTRUCTION

Application filed February 9, 1931. Serial No. 514,438.

This invention relates to improvements in the checker construction in regenerators for use in hot blast stoves, open hearths, soaking pits or heating furnaces and to the regenerative systems. This invention particularly applies to the construction of regenerators in which smaller areas of openings are used at the bottom than at the top, which renders difficult the problem of supporting the checker column at the bottom due to the smallness of the openings and the intervening walls. The checker column is built up out of tile or individual brick.

The bottom support consists of metallic elements which correspond in thickness to the filler brick above and are designed in that fashion in order not to obstruct the checker openings. The employment of these supports necessitates building up the walls in between them of small mitre shape brick which are objectionable on account of their small size and number of joints, which cause them to become loose and drop out. In order to do away with these joints and still permit the use of metal supports under the filler brick, I propose to use a brick in the form of a cross made of one piece, either of brick or of metal which will replace the four mitre brick used at present. Or I propose to use a brick or metal tile containing a number of openings tallying with the checker openings and fitting in with the metal supports of the fillers, or the metal support may be cast integral with this brick or metal support.

It is therefore an object of my invention to construct the supporting members for the checker brick and filler brick in substantially H-shaped form and of similar dimensions, whereby the cross bar of the supporting member serves to support the filler brick and the ends or sides support the checker brick.

It is a further object of my invention to so design the supporting members that the outside contour will conform to the contour of the checker brick supported thereabove, whereby each checker brick rests upon parts of five adjoining supporting members.

Further objects and advantages of my invention will be more readily apparent and

better understood from the following detailed description taken in connection with the attached drawing, in which different forms of construction are illustrated.

In the drawing—

Figure 1 is a plan view showing the manner of associating and positioning a plurality of supporting members.

Figure 2 is a detail vertical section illustrating the manner in which the supporting members are associated with the checker brick and floor tile members.

Figure 3 is a plan view of a single supporting member.

Figure 4 is a side elevation thereof,

Figure 5 is an end view of the supporting member shown in Figure 3, and

Figure 6 is a plan view of a modified construction of supporting member.

Describing first the form of my invention illustrated in Figures 1 to 5, inclusive, it will be understood that vertical columns of checker brick 10 which may be in the form shown of octagonal section, are generally carried directly by the rider tile members 11, if filler brick are not employed. However, if filler brick are loosely inserted in the vertical flow passages in and between these checker brick, it is necessary to employ some form of supporting means therefor. Previous arrangements employing metal bars have been undesirable since small pieces of brick are required to fill up the spaces and are liable to drop out of place.

According to my invention the cross bars which support the filler brick are made integral with head or end portions which cooperate with adjoining members to prevent displacement when in proper position. One form of my filler brick supporting member is illustrated in Figures 1 to 5, inclusive, and designated 12. The supporting member 12 comprises a cross bar 13 which is diagonally disposed with respect to the flow passage thereabove and is preferably rigidly united with head portions 14. Thus the supporting member as a whole is substantially H-shaped in section. Each of the head portions 14 substantially correspond in contour to one-quarter of a checker brick supported there-

above. The manner of associating the individual supporting member 12 is clearly illustrated in Figure 1, in which the cross bar members 13 extend in directions parallel with each other. In this form it will be apparent that each checker brick seats upon five adjoining supporting members, or, in other words, upon the two heads of one supporting member and portions of the heads of four adjoining supporting members.

If desirable a lug 15 may be formed integral with the cross bar 13 and extend in an upward direction to cooperate with filler brick 16 supported thereabove and to enable proper positioning of the checker brick. An additional lug 17 may extend from the bottom of the cross bar corresponding to the upper lug 15 and serve to properly position and hold the supporting members in place. The supporting members may directly rest upon octagonal tile, or brick members 18, which, in turn, rest upon the rider tile members 11, or the supporting members may rest directly on the rider tile 11 themselves.

The supporting members may be constructed entirely of cast metal or the cross bar alone may be of metal integrally cast with brick head portions or the entire support may be formed of brick.

Figure 6 illustrates a modification of my invention when ordinary block-shaped checker brick is employed. The supporting member 20 is shown in this form to extend entirely across the checker chamber and may be described as three Z-members integrally united. Thus the member 20 includes diagonal cross bars 21, metal cross braces 22 and end portions 23. The diagonal members 21 support the filler brick thereabove and the portions 22 and 23 rest upon the rider tile and carry the checker brick.

Therefore, in both forms of my invention the supporting members are so formed that the flow of gas is unrestricted and displacement of the supporting members cannot occur.

Various modifications may be resorted to without departing from the spirit of my invention as expressed in the appended claims.

I claim:

1. In checker work construction, a plurality of octagonal shaped checker brick arranged in vertical columns and forming a plurality of vertical flow passages, filler brick loosely inserted diagonally of the flow passages and supporting members comprising head portions united by an integral cross bar whereby the head portions serve as supports for the checker brick and the cross bar portions serve as supports for the filler brick.

2. A supporting member for checker brick and filler brick comprising a cross bar adapted to be positioned diagonally of the flow passage through a column of checker brick for supporting filler brick therein and head por-

tions integral with the ends of said cross bar adapted to cooperate with the head portions of additional supporting members to form a substantially level base for supporting columns of checker brick.

3. In checker work construction a plurality of hollow checker brick adapted to be superposed in layers to form vertical flow passages, filler brick loosely inserted diagonally of the flow passages and a plurality of supporting members disposed in a layer beneath the checker brick, each of said supporting members including head portions united by an integral cross bar whereby the head portions of said supporting members cooperate to form a substantially level base for supporting the checker brick and the cross bar portions serve as supports for the filler brick.

Signed at New York, New York, this 31st day of January, 1931.

HERMAN A. BRASSERT.
